PUNCHING HAND-TOOL

Pierre Launay, Toulouse, France, assignor to R. K. Price Associates, Inc., New York, N. Y., a company of New York

Application October 20, 1955, Serial No. 541,787

Claims priority, application France October 25, 1954

3 Claims. (Cl. 164—121)

This invention relates to a hand-operated punching tool for cutting two opposed notch enlargements of an initial hole in a sheet metal or a stiff sheet material by one single operation effected from one side only of the material.

In the known punching-tools adapted to that purpose, both notches are cut-out simultaneously, which requires a considerable effort if the material to be punched-out offers a substantial rigidity and/or thickness.

An object of the invention is to provide a punching-tool of the type described, wherein the two notches are cut-out successively in two separate steps of the punching operation, so that the effort to be exerted, at each instant, never exceeds that necessary for cutting-out one single notch.

A further object of the invention is to design the punching members of the tool so that they may be guided in the initial hole during the whole punching operation, which makes the same more accurate.

Still another object of the invention is to make one of the cutting members automatically retractable into the other one upon engagement of the latter into the initial hole to permit passing both cutting members through said hole.

A still further object of the invention is to design the punching members in such a manner that said retraction may be ensured, if desired, merely upon passing said members through the hole, normally to the material.

Yet another object of the invention is to provide means for automatically locking said retractable member in said active position against any reaction force resulting from the punching operation, once both punching members have been passed through said hole.

Preferred embodiments of my invention will be hereinafter described with reference to the accompanying drawings, given merely by way of example and in which:

Figure 1 is a side elevational view with parts broken away and partial sections of a hand operated punching tool according to the invention, shown in rest position.

Figure 2 is a view similar to Figure 1, but showing the tool in operated position.

Figure 3 is a plane view of the tool shown in Figures 1 and 2.

Figure 4 is a cross-sectional view along line 4—4 of Figure 1, of the head of the tool.

Figures 5, 6, 7, 8 and 9 are axial sectional views of the head of the tool, showing five different steps of a punching operation.

Figure 10 shows a hole in a sheet metal before and after the cutting of notches with a tool according to the invention.

In all figures, the corresponding elements have been designated by the same reference numbers.

In the example shown in Figures 1 to 3, the hand-actuation means provided for operating the punching-tool according to the invention are constituted by two hand levers 1 and 2 made of sectional iron and articulated

2

together by means of a pivot axle 3 in the fashion of the handles of pliers.

In this example, the head of the tool is essentially constituted by the active end portion of lever 1 which, for this purpose, is provided with a bore 4 (cf. Figures 5 to 8) in which is reciprocably mounted the punching assembly constituted by a first punching member 5 which is hollow and by a second punching member 6 retractable therein. The punching member 5 terminates at its upper end (in the drawings) in an enlarged portion 7 under which bears the suitably cranked active end of the lever 2 so that when the two levers 1 and 2 are moved towards each other the said lever 2 is capable, while being brought from the position shown in Figure 1 to that shown in Figure 2, to move the enlargement 7 and, hence the punching assembly, axially in a direction causing retraction of the punching members into the head of the tool. The arrangement is such that, once the punching members have been passed through a hole such as 12 in a sheet material, as exposed hereunder, the said retraction determines, by cooperation with the head bearing on the material in the vicinity of said hole, the successive cutting of two opposed notches also as shown in Figure 10. Spring means 8, fixedly secured on the lever 2 by means of a screw 9, continuously urge the reciprocable punching assembly towards its rest position shown in Figure 1, in which it projects out of the head of the tool sufficiently to be passed through an initial hole, with said head remaining on the front side of the material as shown, for example, in Figures 7 and 8. Other spring means 10 are provided to urge the lever 1 and 2 away from each other towards their rest relative position shown in Figure 1. A stud-bolt 11 secured, e. g. on the lever arm 1, acts as an abutment for the other lever 2, so as to limit the relative angular displacement of the two levers towards each other. The retractable punching member 6 is continuously urged towards its active position in which it projects out radially from the hollow punching member 5 by suitable resilient means, positive abutment means being furthermore provided to lock the punching member 6 against retraction, at least during the active steps of a punching operation.

In the example shown in Figures 5 to 8, the said abutment means are constituted by a step 17 adapted to receive the heel of the punching member 6. When said heel is engaged in said step, the punching member 6 is positively locked against radial displacement towards the axis of the punching member 5 as well as against downwards (in Figures 5 to 9) axial displacement with respect to the latter. In the example shown, the resilient means provided to continuously urge the punching member 6 towards its active locked position in steps 17 are constituted, in combination, by a compression spring 13 urging the punching member 6 downwardly through the mushroom 14—15 and by a leaf-spring 16 tending to shift the punching member 6 radially and outwardly as it is pushed downwardly by the mushroom 14—15. The combination of these two spring actions should be capable, on the one hand, of bringing the punching member 6 from a radially and axially retracted position, substantially as shown in Figure 6, to its active position in step 17 as shown in Figures 5, 7, 8 and 9 and, on the other hand, of yieldably holding said punching member 6 in said active position.

When notch enlargements of an initial hole such as 12 (Figures 5 and 10) are to be cut out, the tool is first engaged through said hole, the head of the tool being, if necessary, slightly inclined to facilitate the penetration by hooking first the cutting shoulder of the punching member 5 under the back edge of the plate. There is thus obtained a point of bearing, so that, when the tool is brought into normal relative position with respect to the plate (posi-

tion shown in Figure 6), the cooperation of this point of bearing with the upward pushing action then exerted on the punching member 6 by the diagonally opposite edge of the hole easily causes unlocking of said member. The end face of the punching member 6 offers the shape of an oblique cam surface, so that an axial force exerted downwardly on the tool head from the position shown in Figure 6 causes both radial and axial further retraction of the punching member 6, which is then easily passed, in turn, through the hole 12. As soon as the cutting shoulder of the punching member 5 comes into registration with the back edge of the hole 12, the said punching member 6 is brought back into active position in the step 17 under the combined action of springs 13 and 16. If, now, the hand-actuation means, such as the levers 1 and 2 of Figures 1, 2, and 3 are acted upon, the punching assembly 5—6 is retracted (upwardly in Figures 5 to 9) into the head of the tool. In the example shown, said head is completed by a die member 18 secured in the enlarged lower end of the bore 4 by means of a gudgeon ring 19, a guiding washer 20 being, furthermore, interposed between the die member 18 and the bottom of the end counterbore of bore 4. The inner edge of the die member 18 and the outer edges of the punching members 5 and 6 are precisely matched with each other to permit the usual punching action under shearing forces exerted on the material to be cut-out, on either side of the same, by cooperation between the die member and the punching members.

It is to be noted that both punching members are provided above their cutting shoulders with restricted portions adapted to cooperate with the edge of the initial hole 12, to guide the punching assembly in said hole during the whole punching operation. As the punching assembly is retracted upwardly, from the position shown in Figure 7 to that shown in Figure 9, the following steps of operation take place. The lower edge of the die member 18 is first brought into contact with the material around the initial hole 12. The left edge of the said hole is then clamped between said die member and the cutting shoulder of the punching member 6 and cut out by shearing action as shown in Figure 8.

It will be pointed out that during this step, the punching member 6 is exclusively subjected to downwards axial forces possibly with a small radial inwards component, so that it remains perfectly locked in the step 17.

The cutting shoulder of the punching member 5 is then brought, in turn, into contact with the lower right edge of the hole 12, and cuts out the second notch by shearing action in cooperation with the die member 18 as shown in Figure 9. The axial spacing between the two cutting shoulders is preferably chosen at least equal to the maximum thickness of the sheet materials to be punched out, so as to avoid any overlapping between the two separate steps of the punching operation.

In a general manner, while I have, in the above description, disclosed what I deem to be practical and efficient embodiments of my invention, it should be well understood that I do not wish to be limited thereto as there

might be changes made in the arrangement, disposition and form of the parts without departing from the principle of the present invention.

In particular, while I have indicated how the head of the tool may be inclined at first to facilitate its engagement into the initial hole, it is to be noted that the special arrangement of the abutment means 17 and the resilient means 13, and 16 shown in the drawings, permits passing the head of the tool normally through the hole under retraction of the punching member 6.

What is claimed is:

1. A hand-operated punching tool for cutting two opposed notch enlargements of an initial hole in a sheet metal or other stiff sheet material by a single operation from one side only of the material, said tool comprising a head, a die member mounted on said head and adapted to rest on said material in the vicinity of said hole, a first hollow punching member reciprocably mounted in said head and extending past said die member, a second punching member mounted in said first punching member and retractable thereinto from an active position to permit passing said first punching member through said initial hole, resilient means to continuously urge said second punching member towards said active position, abutment means to lock said second punching member in said active position, each one of said punching members having a restricted portion adapted to be accommodated and guided in said hole and a radially projecting cutting shoulder adapted to cooperate with said die member for cutting, by a shearing action, one of the desired notches, the cutting shoulder of said second punching member being spaced axially from that of said first punching member, and hand-actuation means adapted to retract said first punching member axially into said head for successively cutting said two notches in cooperation with said die member.

2. A punching hand-tool according to claim 1, wherein said abutment means are constituted by a step formed in said first punching member to receive the heel of said second punching member to thereby lock the same positively against any displacement under reaction forces resulting from said shearing action, said resilient means being adapted to yield under a relative axial force exerted between said two punching members and tending to retract said second punching member axially into said first one.

3. A punching hand-tool according to claim 2, wherein said resilient means comprise a first spring continuously urging said second punching member axially towards said step and a second spring adapted to shift said second punching member radially and outwardly to guide its heel towards said step.
